(57) CLAIM

The ornamental design for a lotion applicator, as shown and described.

DESCRIPTION

FIG. 1 is a perspective view of a lotion applicator;
FIG. 2 is an elevational view of a first side of the lotion applicator, the opposite second side view being a mirror image thereof;
FIG. 3 is a rear end elevational view of the lotion applicator;
FIG. 4 is a front end elevational view of the lotion applicator; and,
FIG. 5 is a top plan view of the lotion applicator, the bottom plan view being a mirror image thereof.
